UNITED STATES PATENT OFFICE.

JOSEPH BARTON, JESSE MELBOURN, FOREST NEEDHAM, AND JOHN G. GREEN, OF CLE ELUM, WASHINGTON.

LANTERN.

1,102,854.

Specification of Letters Patent.

Patented July 7, 1914.

Application filed June 23, 1913. Serial No. 775,335.

To all whom it may concern:

Be it known that we, JOSEPH BARTON, JESSE MELBOURN, FOREST NEEDHAM, and JOHN GEORGE GREEN, citizens of the United States, and residents of Cle Elum, in the county of Kittitas and State of Washington, have invented certain new and useful Improvements in Lanterns, of which the following is a specification.

10 Our invention relates to lanterns, and more especially to lanterns of the kind used in connection with acetylene gas, our more particular purpose being to provide a construction in which the water tank and the 15 carbid container, associated with the making of the gas, are connected together by the drop pipe, and removable as a unit for purposes of lighting the lamp.

Our invention further relates to certain 20 details of construction suitable for use with lanterns and related devices of this general type.

Reference is made to the accompanying 25 drawings forming a part of this specification, and in which like letters indicate like parts.

Figure 1 is a side view partly in elevation and partly in section showing our improved lantern complete. Fig. 2 is a detail view 30 showing in perspective the water tank, the carbid container connected therewith by a drop pipe, and the ventilation dome carried by the water tank, these parts being removed from the lantern. Fig. 3 is a perspective of the lantern frame, the top ring being thrown back, and, Fig. 4 is a section 35 on the line 4—4 of Fig. 1, looking in the direction of the arrow.

A number of standards 5 support a top 40 ring 6, a middle ring 7, a waist ring 8, and a base ring 9. These parts collectively form a lantern cage, and are of the usual or any desired construction. The bail of the lantern is shown at 10, and is pivotally connected with the ears 10^a, which are carried by the top ring 6.

A supporting ring is shown at 11, and is provided with an upwardly extending flange 12 made of sheet metal, and so formed as 50 to be threaded. A collar 13 is secured upon the supporting ring 11, and extends slightly into the annular flange 12. The supporting ring 11 is pivotally mounted upon the top ring 6 by a hinge 14, and is provided 55 with a clasp 15 for engaging the top ring

6, at a point thereof opposite the location of the hinge 14.

Carried by the waist ring 8 is a holder 16 of substantially cylindrical form. This holder adjacent its bottom is provided with 60 ventilation holes 17 and 17^a arranged in two rows as indicated more particularly in Figs. 1 and 3. The holder 16 at its bottom edge is provided with a number of tongues 18 bent upwardly, and at their upper ends 65 curved slightly outward as indicated in Fig. 1. The holder 16 is further provided with a metallic lining 21, and with a ring 21^a, this ring having a flange 22 cupped outwardly and engaging the upper edge of 70 the ring 20. The ring 21^a is also provided with an annular flange 23 extending downward. The lantern globe is shown at 14, and rests on the ring 21^a.

The carbid container is shown at 25, and 75 is essentially a small tank of cylindrical form provided with a bottom 26, and with a rounded annular portion 27, adapted to engage the curved portion 19 of the tongues 18. The carbid container is further provided with a frusto-conical portion 28, and with an annular flange 29, this flange being threaded. A burner cap is shown at 30, and is provided with an annular portion 31 80 threaded to fit the threaded portion 29. The 85 burner cap is further provided with an annular portion 32 which engages a gasket 33, the latter encircling the frusto-conical portion 28. A burner 34 is carried by the 90 burner cap 30. The drop pipe is shown at 35, and extends through the burner cap 30 to a point adjacent the bottom 26 of the 95 container. The water tank is shown at 37, and is essentially a reservoir of annular form. It is provided internally with a double wall consisting of two concentric cylindrical members 38, 39, these members being flared outwardly at their bottoms. Between the members 38—39 is a loose filling 40 of 100 heat insulating material, such as asbestos. The water tank 37 is provided with an opening 41, and fitting into this opening is a closure plug 42 provided with a hole 42^a for 105 permitting vapor, if any be formed by the water, to readily make its escape. The 110 water space is shown at 43, and has a general annular form.

The bottom of the water tank is provided with a valve seat 44, and a needle valve 45 detachably engages the seat 44. The needle 110

valve is at its upper end provided with a handle 46, by which it may be turned, this handle serving also as an indicator for disclosing the position of the valve relatively to its seat. A circular scale 46^a is placed upon the upper surface of the water tank 37. The operator by noting the position of the handle 46 relatively to this scale can readily determine, within reasonable limits, the amount of water flowing from the tank. The needle valve extends through an airtight bearing 47.

Mounted upon the upper surface of the annular water tank is a ventilation dome 50 provided with openings 51. This ventilation dome is engaged rigidly with the water tank and is removed therewith whenever the tank, and parts carried by it, are taken from the lantern.

20 The burner 34 is connected with a short pipe 52, and mounted within this pipe is a filter 53 made of spongy material, for the purpose of preventing impurities from entering the pipe 53.

25 The bottom of the water tank is provided with a bearing tube 54, secured rigidly to it and extending downwardly from it, the drop pipe 35 extending through this bearing tube and being braced and strengthened by it. The bottom of the water tank is provided with a threaded flange 55 formed of sheet metal and engaging the threaded portion 12 of the supporting ring 11.

The operation of our device is as follows: 30 The parts being assembled, and arranged as above described, and as shown more particularly in Fig. 1, the lantern is ready for use. The carbid container is filled by removing the closure plug 42, and pouring water through the hole 41. The needle valve 45 being now turned by aid of the handle 46, water feeds slowly downward from the water tank through the drop pipe 35 and into the carbid container 25, this carbid container having been previously filled with calcium carbid. The acetylene gas is generated by action of the water upon the carbid. This gas passes upwardly through the filter 55, and the pipe 52 of the burner 34.

50 In order to light the lantern there is no necessity to remove the globe 24. The operator grasps the water tank 37, and by turning it relatively to the supporting ring 11 unscrews it. Then by lifting the water tank 55 straight upward the drop pipe 35, carrying with it the carbid container 25, is removed along with the dome 50, as will be understood from Fig. 2. The lamp being lighted, the parts shown in Fig. 2 are replaced. It is 60 not even necessary to throw the supporting ring 11 into the position indicated in Fig. 3 in order to remove the parts shown in Fig. 2 and to light the burner.

It will be noted that the double inner wall 65 of the water tank serves, to some extent, as

a part of the chimney, and that the water carried by the water tank tends to prevent the lantern from becoming excessively hot. The water is not heated, however, to the boiling point. The dome 50 is, by its proximity to the water tank, and by the heat conductivity of parts connecting it therewith, prevented from becoming sufficiently hot to burn the hand of the operator should he happen to touch the dome accidentally.

We do not limit ourselves to the precise construction shown, as variations may be made therein without departing from the spirit of our invention.

We claim:

1. In a lantern adapted for acetylene gas, the combination of a lantern frame, a holder mounted therein and having a general annular form for supporting the carbid container, said holder being provided with tongues bent inwardly and upwardly, a carbid container provided with a rounded annular portion for engaging said tongues, a drop pipe connected with said carbid container, a water tank connected with said drop pipe, and means for securing said water tank upon said lantern frame.

2. A lantern adapted for acetylene gas, comprising a lantern frame, a support ring mounted thereupon and provided with an annular flange having a thread, a water tank having a substantially annular form and provided with an annular flange having a thread mating said first mentioned thread, a water tank having a double inner wall, 100 heat-insulating material located within said double wall, a ventilation dome carried by said double inner wall and provided with openings, a drop pipe connected with said water tank, and a carbid container connected with said drop pipe.

3. A lantern for acetylene gas, comprising a lantern frame, a holder carried thereby and having a general annular form, said holder being provided with ventilation holes and with tongues bent upwardly, a carbid container provided with a rounded portion for engaging said tongues in order to provide a spring seat for said carbid container, a drop pipe connected with said carbid container, a water tank connected with said drop pipe and removable with said drop pipe and said carbid container as a unit, said water tank being provided with an annular threaded portion, and a supporting ring mounted upon said lantern frame and provided with an annular threaded portion mating said annular threaded portion of said water tank.

4. In a lantern adapted for acetylene gas, 125 the combination of a lantern frame, a carbid container, a holder mounted upon said frame and having a general annular form for supporting the carbid container, a globe carried by the frame above said carbid container, a

water tank disposed above said globe, and a drop pipe rigidly secured to said water tank and to said carbid container and extending within the latter, said water tank, drop pipe and carbid container being removable as a unit.

5. In a lantern adapted for acetylene gas, the combination of a lantern frame, a carbid container, a holder mounted upon said frame and having a general annular form for supporting the carbid container, a globe carried by the frame above said carbid container, a water tank disposed above said globe, a drop pipe secured to said water tank and extend-

ing downwardly through said globe and being secured to said carbid container, and a burner carried by said carbid container, the upper end of the globe being of sufficient size to permit the removal of the carbid container and drop pipe, when the water tank is removed.
